STAY-LOG STRUCTURE FOR VENEER LATHES

Joseph T. Mengel, Knoxville, Tenn.

Application July 11, 1952, Serial No. 298,375

7 Claims. (Cl. 144—214)

1

The present invention relates in general to veneer lathe machines for cutting veneer from logs, blocks or flitches of wood, and more particularly relates to a staylog mounting unit therefor for positioning the logs or blocks of wood so as to maintain the figure or character of the veneer grain more or less uniform throughout the cutting operation.

Heretofore, cutting of veneer has been practiced primarily either by mounting a whole log for rotation about its central axis against an advancing knife to form a continuous sheet of veneer, known as round cutting, or by mounting blocks or flitches of wood on a rotating support, known as a staylog, and rotating the block or flitch about the axis of the staylog, and intermittently advancing a knife toward the axis of rotation an amount equal to the thickness of the veneer to be cut to successively form single veneer strips during each rotation of the staylog. In most cases, however, no provision was made for periodic adjustment of the angle of the grain of the wood block or flitch in relation to the cutting face of the knife so as to maintain the figure or character of the veneer grain uniform during the cutting operation.

One modification of this arrangement, designed to avoid the appearance of undesired grain patterns during such cuts, involved the addition of intermediate wedge-shaped plates to be inserted between the supporting face of the staylog and the block or flitch, which served as a bearing plate for the flitch to incline the flitch relative to the staylog.

An object of the present invention is the provision of a novel staylog mounting assembly for veneer lathes which permits the periodic adjustment of the grain angle of the block or flitch relative to the cutting knife in an advantageous manner to provide uniformity of grain pattern.

Another object of the present invention is the provision of a novel staylog mounting unit for veneer lathes by which the plane of the bearing face of the staylog and the grain angle of the block or flitch to be mounted thereon can be adjusted relative to the cutting face of the knife so as to selectively change the angle of attack thereof.

Another object of the present invention is the provision of a novel staylog mounting unit for veneer lathes by which the grain angle of the block or flitch to be mounted on the staylog may be successively shifted relative to the cutting face of the knife so as to provide veneer sheets of more or less uniform grain pattern throughout the cutting operation.

2

Other objects, advantages and capabilities of the present invention will become apparent from the following detail description, taken in conjunction with the accompanying drawings, wherein only a preferred embodiment of the invention is illustrated.

In the drawings:

Figure 1 is a front elevation of a conventional veneer lathe, with the staylog mounting means of the present invention incorporated therein;

Figure 2 is a vertical transverse section taken along the lines 2—2 of Figure 1, illustrating the staylog mounting means of the present invention, with the flitch and staylog disposed in position for cutting the upper portion of the flitch;

Figure 3 is a section view taken through a portion of the staylog mounting means and associated portions of the lathe, taken along the lines 3—3 of Figure 2;

Figure 4 is an exploded perspective view of the staylog, mounting means therefor and one of the staylog supporting face plates;

Figure 5 is a view of the staylog and supporting mechanism therefor illustrated in Figure 2, with the staylog and flitch positioned for cutting the middle portions of the flitch; and

Figure 6 is a view of the staylog and supporting mechanism therefor illustrated in Figure 2, with the staylog and flitch positioned for cutting the innermost portions of the flitch.

Referring to the drawings, wherein like reference characters designate corresponding parts throughout the several figures, and particularly referring to Figure 1, the reference character 10 designates a conventional staylog type of veneer lathe of the type with which the staylog mounting mechanism of the present invention is to be employed. These conventional staylog veneer lathes are usually provided with a large bed or base 11 supporting a plurality of aligned bearing elements 12, having aligned bearing apertures therein for supporting trunnions 13 extending from a pair of aligned circular face plates 14. Power is applied to the trunnions 13 to rotate the face plates 14 in synchronism about the trunnion axis at a controlled speed through the interengagement of gears 15 with gears 16 on a suitable drive shaft 17. The speed at which these face plates 14 are initially driven is usually very slow compared to normal running speed.

The staylog for such a veneer lathe is indicated generally by the reference character 20 and consists of a generally cylindrical body of metal having a sector of the wall thereof extending the length of the staylog deformed to produce a pair of flanges 21 and a bearing face 22, the

flanges having a series of apertures through which screws 23 are extended and driven into a block or flitch of wood, indicated at 24, to securely mount the flitch on the flitch supporting face 22.

The staylog 20 is provided with cylindrical trunnions 25 projecting from each end thereof, which are usually rigidly held in an accommodating aperture in the face plates 14 with the flitch supporting face 22 disposed in a plane perpendicular to the radial axis of the face plate extending through the center of the staylog. The axis of the staylog may either be disposed coincident with the axis of the face plates 14 or may be off-center therefrom, in this conventional construction.

Such lathes are also provided with a knife carriage, generally indicated at 26, which is slidably mounted for movement toward and away from the axis of the trunnions 13. This carriage 26 adjustably mounts a knife 27 having a cutting edge disposed parallel to the axis of the trunnions 13. A guard plate 28 is usually associated with the knife 27 on the knife carriage 26 to assist in regulating the thickness of the veneer slices.

In accordance with conventional practice, the log flitches are first bolted to the staylog 20, and the knife carriage 26 is brought up to initial cutting position. The face plates 14 and staylog 20 are then slowly rotated to make the first several cuts, after which the conventional automatic knife carriage feed is utilized to advance the knife toward the axis of the trunnions 13. These automatic feeds advance the knife the required distance during the interval following the departure of the trailing edge of the flitch from the knife and before the presentation of the leading edge of the flitch to the knife edge in the next successive rotation cycle.

The veneer lathe construction and operating procedures thus far described are representative of lathes and procedures well known in the industry. U. S. Patent No. 1,574,037 to Kessler, dated February 23, 1926, and No. 1,786,460 granted December 30, 1930, to Stone, are representative disclosures of the conventional lathe described above except for the specific staylog structure disclosed therein. Since the staylog type of veneer lathe is so well known and broadly disclosed in these patents, and since the present invention is directed to the staylog mounting structure per se, no further description of such lathe is believed necessary.

Figures 2 to 6 illustrate the specific mechanism which is employed to intercouple the staylog 20 with the face plate 14 to permit the staylog 20 and the block or flitch 24 mounted thereon to be adjusted to various angles relative to the cutting face of the knife 27 so as to provide a more or less uniform grain pattern in the veneer sheets successively cut from the block 24. To this end, each of the circular face plates 14 are provided with a generally U-shaped member 30 forming a retaining plate which is welded or otherwise securely held on the face plate 14. This U-shaped member 30 is provided with legs 31, 32, which are each arranged parallel to a diametric axis of the face plate 14 and equally spaced therefrom, the adjacent faces of each of the legs 31, 32 being oppositely beveled as indicated at 31', 32' to define a dove-tail slot 33 opening at one edge of the face plates 14 and centered relative to the axis of the face plate.

A dove-tail bearing block 34 is slidably disposed within the dove-tail slot 33, and is pro-

vided with a bearing aperture 35 to receive one of the trunnions 25 of the staylog 20. Suitable means such as a rod 36 threaded at one end 36' into a suitable threaded aperture 34' of the bearing block 34 and anchored for rotation in the bridge 30' of the U-shaped member 30, may be provided to hold the bearing block 34 in the desired position of adjustment along the axis of the dove-tail slot 33.

10 An elongated arm 37 is to be associated with each end of the staylog 20. The arm 37 is provided with an aperture 38 through which the staylog trunnion 25 is to be projected and the arm welded or otherwise suitably anchored to the staylog 20.

15 The end of each arm 37 is bifurcated to define a slot 39 in which a reciprocating latching tongue 40 is disposed to be selectively projected beyond the end of the arm 37 or withdrawn into the slot 39. The control means for this latch tongue 40 consists of a connecting rod or link 41 which is coupled at one end to the tongue 40 and extends through an axial bore 42 into an intermediate recess 43 in the arm 37. The end of the rod 41 projecting into the recess 43 is coupled to a slotted cam plate 44 pivotally mounted within the recess 43. A pin 41' on the end of the rod 41 extends through the inclined slot 44' in the slotted cam plate 44, so that rotation of the handle 45 of the cam plate 44 draws the rod 41 and latch tongue 40 connected therewith axially of the arm 37 to withdraw the tongue 40 into the recess 39. The cam plate 44 is normally disposed so that the handle 45 extends alongside the arm 37. Suitable locking means such as the outstanding lug 46 having a threaded bolt 46' therein which may be positioned to overlie and hold the handle 45 in such position is preferably provided on the arm 37.

20 An arcuate latch plate 47 conforming substantially to the configuration of the circular face plates 14 is securely mounted to the bridge portion 30' of the U-shaped member 30 as by bolts 47', and is provided with an arcuate recess 48 in the end thereof disposed toward the arm 37 to accommodate the arms 37 during rotation about the axis of the staylog trunnions 25. Integral stop elements 49 are formed at each end of the arcuate recess 48 to limit rotation of the arms 37 about the axis of the staylog trunnions 25 to approximately fifty degrees. A series of notches 50, 51 and 52 are provided at spaced points along the arcuate recess 48, the notches 50 and 52 being disposed to accommodate the projecting latch tongue 40 when the arm 37 is disposed at either limit of the recess 48 in contact with the abutment stops 49, 49', respectively. The intermediate notch 51 is disposed to accommodate the projecting latch tongue 40 and position the arm 37 when the axis of the arm 37 is disposed parallel to the axis of the dove-tail slot 33.

25 This adjustment mechanism for the staylog is provided to effect adjustment of the grain angle of the block or flitch 24 relative to the face of the knife 27 as the cutting of veneer strips from the block 24 proceeds from the outer tip 24' thereof toward the inner portion 24'' of the flitch. The flitches or blocks used in this type of cutting operation are generally quarter round flitches so that the medullary or wood rays indicated by the reference character 55 radiate from one longitudinal corner of the flitch. The arcuate lines 56 and 57 of Figure 5 divide the flitch into outer, intermediate and inner cutting

zones 58, 59 and 60, respectively, of the flitch 24.

It will be apparent that with the fixed type of staylog heretofore in common use, which maintains the flitch in the position illustrated in Figure 5 throughout the cutting operation, the mean angle of the medullary rays relative to the arcuate cutting axis in the intermediate and inner cutting zones 59 and 60 would be markedly different from that in the outer zone 58, so that the grain pattern of the veneer sheets cut from the intermediate and inner zones would differ markedly from those cut from the outer zone 58.

The operation of the present invention to avoid this wide disparity in grain pattern is substantially as follows. The arms 37 controlling the orientation of the staylog 20 and flitch supporting face 22 are initially positioned as illustrated in Figure 2, with the projecting latch tongue 40 seated in the notch 50 of the arcuate latch plate 47. The tongue 40 is held in this position by virtue of the screw 48' overlying the handle 45 of the cam plate 44. The power means for the lathe is then energized to drive the face plates 14 carrying the staylog 20 and flitch 24 about the axes of the face plate trunnions 13 to successively bring the flitch into contact with the knife 27 during each cycle of revolution of the face plates 14. This is repeated until the knife has cut away the outer zone 58 of the flitch down to approximately the arcuate line 56 at which time the lathe is deenergized.

The screw 56' is then rotated out of contact with the arm 45 of the cam plate 44 and the plate 44 is pivoted upwardly to withdraw the latch tongue 40 from the notch 50 in the latch plate 47. The arms 37 are then rotated within the recess 48 to dispose the latch tongue 50 over the recess 51 and the cam plate 44 rotated downwardly to project the tongue 40 into the recess 51, the cam plate 44 being then locked in this position by means of the screw 46'. The lathe is again energized and operated with the staylog 20 in this condition until the flitch is cut down to approximately the line 51, at which time the lathe is again deenergized, the tongue 40 withdrawn from the notch 51, the arms 37 rotated to the position illustrated in Figure 6, and the latch tongue 40 again locked in seated condition in the notch 52. The lathe may then be again energized and the log cut down through the inner zone 60 thereof.

By shifting the plane of the flitch supporting plate 22 of the staylog 20 relative to the face of the knife 27 in the manner just described, the cutting axis of the blade through the flitch will be varied to substantially compensate for the charges in the mean angle between the medullary rays of the flitch and the knife as the flitch is cut down to the intermediate and inner zones thereof, thus producing a more or less uniform figure or character in the veneer grain pattern throughout the cutting of the entire flitch. This is accomplished in a simple manner without requiring the attendance of a skilled operator, as the positions of adjustment are already indicated on the latch plate 47 by the notches 50, 51 and 52, and the staylog and flitch are securely held in the position of adjustment in a manner avoiding misalignment of the flitch by impact with the knife by the latch tongue 40 seated in the appropriate recess in the latch plate 47.

While but one specific embodiment of the invention has been particularly shown and described, it is apparent that various modifications may be made in the invention without departing

from the spirit and scope thereof, and it is desired, therefore, that only such limitations shall be placed thereon as are imposed by the prior art and are set forth in the appended claims.

5 What is claimed is:

1. In a veneer lathe including a rotatable staylog having a flitch supporting face, means for adjustably supporting said staylog in said lathe comprising a pair of rotatably mounted driven supporting plates for said staylog having bearing means for journaling said staylog between said plates, a projecting arm rigidly carried by said staylog, latch means disposed at the end of said arm, and locking means rigidly supported on at least one of said supporting plates cooperating with said latch means to lock said projecting arm at selected angles with respect to a reference plane extending through the axes of said supporting plates and said staylogs for varying the angular relation of said flitch supporting face in said lathe.

2. In a veneer lathe including a rotatable staylog having a flitch supporting face, means for adjustably supporting said staylog to vary the angle of attack of a flitch supported thereon relative to a knife on said lathe comprising a pair of rotatably mounted driven supporting plates for said staylog having eccentrically disposed bearing means for journaling said staylog for rotation about the axis of said staylog, a projecting arm rigidly carried by said staylog, latch means disposed at the end of said projecting arm, and locking means rigidly supported on at least one of said supporting plates cooperating with said latch means to lock said projecting arm at selected angles oppositely inclined to and aligned with a reference plane extending through the axes of said supporting plates and said staylog.

3. In a veneer lathe including a rotatable staylog having a flitch supporting face, means for adjustably supporting said staylog to vary the angle of attack of a flitch supported thereon relative to a knife on said lathe comprising a pair of rotatably mounted driven supporting plates for said staylog having eccentrically disposed bearing means for journaling said staylog for rotation about the axis of said staylog, an integral projecting arm disposed on at least one end of said staylog to overlie one of said supporting plates, latch means disposed at the end of said projecting arm to selectively project therefrom, and an anchor plate rigidly supported on at least one of said supporting plates having keeper means to receive said projecting latch means for locking said projecting arm and staylog at selected angles oppositely inclined to and aligned with the projected plane of the axes of said supporting plates and staylog.

4. In a veneer lathe, a pair of driven circular plates mounted for rotation about a transverse axis of said lathe, a staylog having its ends journaled in said circular plates for rotatably supporting said staylog about an axis parallel to and spaced radially from said transverse lathe axis, and means for adjusting the orientation of said staylog relative to a plane intersecting said staylog and transverse lathe axes comprising an arm rigidly carried by such staylog and projecting radially therefrom, a locking plate rigidly supported on at least one of said circular plates, and latch means on said arm to be selectively intercoupled with complementary latching means on said locking plate for locking said arm and staylog at selected angles of inclination relative to said supporting plates.

5. In a veneer lathe of the type including a rotatable staylog having a flitch supporting face, supporting means for said staylog to vary the angle of attack of a flitch supported thereon relative to a knife on said lathe comprising a pair of driven circular plates journaled for rotation about a transverse axis of said lathe, bearing means mounted on said plate for journaling said staylog for rotation on an axis spaced from the transverse lathe axis, an integral arm on at least one end of said staylog projecting perpendicularly from said staylog and having a latching tongue projecting from the end thereof, and a locking plate rigidly supported on at least one of said circular plates having recesses for receiving said latching tongue at selective positions of said arm oppositely inclined to and aligned with a plane intersecting said transverse lathe and staylog axes.

6. In a veneer lathe of the type including a rotatable staylog having a flitch supporting face, supporting means for said staylog to vary the angle of attack of a flitch supported thereon relative to a knife on said lathe comprising a pair of driven circular plates journaled for rotation about a transverse axis of said lathe, bearing means mounted on said plate for journaling said staylog for rotation on an axis spaced from the transverse lathe axis, integral arms projecting perpendicularly from said staylog at each 30 end thereof and having a latching tongue projecting from the ends thereof, and a locking plate rigidly supported on each of said circular plates having recesses for receiving said latching tongue at selective positions of said arm 35

oppositely inclined to and aligned with a plane intersecting said transverse lathe and staylog axes.

7. In a veneer lathe of the type including a rotatable staylog having a flitch supporting face for presenting a flitch carried thereon cyclically to a fixed veneer knife, supporting means for said staylog to vary the angle of attack of a flitch supported thereon relative to the knife on said lathe comprising a pair of driven circular plates journaled for rotation about a transverse axis of said lathe, bearing means mounted on said plate for journaling said staylog for rotation on an axis spaced from the transverse lathe axis, integral arms projecting perpendicularly from said staylog to overlie said circular plates and having a latching tongue projecting from the ends thereof, and a locking plate rigidly supported on each of said circular plates having recesses for receiving said latching tongue at selective positions of said arm oppositely inclined to and aligned with a plane intersecting said transverse lathe and staylog axes.
